(57) **CLAIM**

The ornamental design for a mouthpiece of an electronic vaping device, as shown and described.

DESCRIPTION

FIG. 1 is a front-top perspective view of a mouthpiece of an electronic vaping device;

FIG. 2 is a front view of the mouthpiece of an electronic vaping device shown in FIG. 1;

FIG. 3 is a rear view of the mouthpiece of an electronic vaping device shown in FIG. 1;

FIG. 4 is a left side view of the mouthpiece of an electronic vaping device shown in FIG. 1;

FIG. 5 is a right side view of the mouthpiece of an electronic vaping device shown in FIG. 1;

FIG. 6 is a top view of the mouthpiece of an electronic vaping device shown in FIG. 1; and,

FIG. 7 is a bottom view of the mouthpiece of an electronic vaping device shown in FIG. 1.

(Continued)

The broken lines in the drawings depict portions of the mouthpiece of an electronic vaping device that form no part of the claimed design.

1 Claim, 7 Drawing Sheets
